UNITED STATES PATENT OFFICE

169,859

STAPLE PULLER

William H. Misson, Los Altos, Calif., assignor to
Zip Products Co., a partnership

Application January 9, 1953, Serial No. 23,083

Term of patent 14 years

(Cl. D74—1)

To all whom it may concern:

Be it known that I, William H. Misson, a citizen of the United States and a resident of Los Altos, county of Santa Clara, State of California, have invented a new, original, and ornamental Design for a Staple Puller, of which the following is a specification, reference being had to the accompanying drawing, forming a part thereof.

Figure 1 is a perspective view of a staple puller showing my new design;

Figure 2 is a side elevation thereof;

Figure 3 is a front elevation thereof; and

Figure 4 is a bottom view thereof.

I claim:

The ornamental design for a staple puller, as shown.

WILLIAM H. MISSON.
